UNITED STATES PATENT OFFICE.

EDWARD F. BRAGG, OF CAMBRIDGE, ASSIGNOR TO THE AUTOMATIC RUBBER MIXER COMPANY, OF BOSTON, MASSACHUSETTS.

ROLL FOR INDIA-RUBBER MIXING AND CALENDERING MACHINES.

SPECIFICATION forming part of Letters Patent No. 508,272, dated November 7, 1893.

Application filed April 3, 1893. Serial No. 468,838. (No model.)

To all whom it may concern:

Be it known that I, EDWARD F. BRAGG, of Cambridge, county of Middlesex, State of Massachusetts, have invented an Improvement in Rolls for India-Rubber Mixing and Calendering Machines, &c., of which the following description, in connection with the accompanying drawings, is a specification, like letters on the drawings representing like parts.

Application, Serial No. 450,311, filed October 29, 1892, by Robert Cowen and Edward F. Bragg, shows a roll for india-rubber mixing and calendering machines, &c., wherein a cooling fluid as water is introduced through journals at one end of the roll and is circulated through longitudinal peripheral passages to the outlet at the opposite journal of the roll to thereby cool the periphery of the roll to prevent its heating and injuring the material being worked. This invention has for its object to provide another form of roll for accomplishing the same result. Whereas in the roll shown in the application referred to the peripheral passages extend longitudinally or parallel with the axis of the roll, in this my new form of roll, the peripheral passages are made annular, *i. e.*, extending around the roll circumferentially in planes perpendicular to the axis of the roll, said annular passages being connected in suitable manner with the axial inlet and outlet to form communications between the same.

Figure 1, represents in vertical section a roll embodying this invention, the section being taken on the dotted line $x-x$, Fig. 2; Fig. 2, a vertical section of the same taken on the dotted line $x'-x'$, Fig. 1; and Fig. 3, a vertical cross section on the dotted line x^2-x^2 , Fig. 1.

Referring to the drawings A, represents a solid metal roll such as used for rolling and mixing rubber, &c., such roll being provided with end journals a, a , as shown.

B, B' represent respectively an axial inlet and outlet, the same entering the roll through the journals at opposite ends and extending nearly or quite the entire length of the roll proper, and preferably being offset slightly within the roll, as shown, in order that they may run parallel with and close to each other.

The roll in accordance with this invention is provided with a series of annular or circumferential circulating passages c, c , located preferably close to the periphery of the roll and embedded therein, such annular passages being, in the construction shown, located in planes perpendicular to the axis of the roll. The annular circulating passages c, c , are each connected at preferably diametrically opposite points with the inlet and outlet respectively by the radial inlet and outlet pipes c', c^2 , as shown. In the preferred construction, as in Fig. 1, the radial inlet passages for the successive annular passages enter the latter at diametrically opposite sides of the roll, *i. e.*, following the entrance passage into the roll, the first radial inlet pipe leads from the axial inlet to the left to the first annular passage, while the radial inlet for the second annular passage leaves the axial inlet at the right; the third to the left, the fourth to the right, &c., alternately throughout the entire length of the roll, the return axial pipes likewise leading to the axial outlet alternately from the opposite sides of the roll, the result being that when the cooling fluid, as water, is introduced into the roll through the axial inlet B, said fluid will reach the first annular passage at one side of the roll, the second at the opposite side of the roll, and so on throughout the entire series of annular passages, the result being that the flow of the fluid through successive annular passages is in opposite directions from the coolest to the hottest parts of the passages, thereby obtaining a uniform mean temperature between the hottest and coolest portions of the cooling fluid, such uniform temperature being quite essential when the roll is used in many classes of work.

I prefer to construct the roll in the manner illustrated in the drawings wherein the several passages are formed by suitable pipes placed in the mold before casting, the metal of the roll being thereafter cast about these pipes, leaving the passages free and clear. I desire it to be understood, however, that these passages may be formed in any other manner desired, the gist of this invention consisting in an axial inlet and outlet connected one with the other by annular peripheral cir-

culating passages whereby a cooling fluid introduced at the inlet is caused to circulate through the annular passages within the periphery of the roll to cool the latter before flowing out through the outlet. It matters not, of course, that the annular circulating passages do not lie in planes exactly perpendicular to the axis of the roll, although such is the preferred construction.

10 I claim—

1. A metal roll having both an axial inlet and outlet, and a series of independent annular circulating passages connecting the same, substantially as described.
- 15 2. A metal roll having both axial inlet and outlet passages extending substantially the entire length of the roll, in combination with a series of independent annular passages located near the periphery of the roll, and radial passages connecting the same with said inlet and outlet passages whereby fluid introduced through the inlet is caused to flow
- 20

through said annular passages to the outlet, substantially as described.

3. A metal roll having axial inlet and outlet passages extending substantially the entire length of the roll, in combination with a series of independent annular passages and radial passages connecting opposite points of each with said inlet and outlet passages respectively, the successive radial passages leading from the inlet passage extending in opposite directions, whereby fluid of the same temperature is introduced into successive annular passages at opposite sides of the roll whereby a mean temperature is obtained, substantially as described.

In testimony whereof I have signed my name to this specification in the presence of two subscribing witnesses.

EDWARD F. BRAGG.
